Ernest L. Shepard, Fairfield, Maine, assignor, by mesne assignments, to The Canal National Bank of Portland, Portland, Maine, a national banking association, and William B. Nulty, Portland, Maine, as trustees

Application January 10, 1948, Serial No. 143,635

Term of patent 14 years

(Cl. D58—13)

To all whom it may concern:

Be it known that I, Ernest L. Shepard, a citizen of the United States, residing at Fairfield, in the county of Somerset, State of Maine, have invented a new, original, and ornamental Design for Pack for Fragile Articles, of which the following is a specification, reference being had to the accompanying drawing, forming part thereof.

Fig. 1 is a perspective view of a pack for fragile articles, showing my new design, the pack
 being in open position;

Fig. 2 is a perspective view thereof shown in closed position;

Fig. 3 is an end elevational view thereof shown in folded position; and

Fig. 4 is a plan view of the pack in fully open position.

I claim:

The ornamental design for a pack for fragile articles, as shown.

ERNEST L. SHEPARD.
